(57) **CLAIM**

The ornamental design for a storage box, as shown and described.

DESCRIPTION

FIG. 1 is a perspective view in the closed configuration with the three parts assembled together of a storage box, showing my new design;

FIG. 2 is a perspective view of the storage box in a detached status;

FIG. 3 is a perspective view of the first part of the storage box;

FIG. 4 is another perspective view thereof;

FIG. 5 is a front view thereof;

FIG. 6 is a rear view thereof;

FIG. 7 is a left side view thereof;

FIG. 8 is a top plan view thereof;

FIG. 9 is a bottom plan view thereof;

FIG. 10 is a perspective view of the second part of the storage box;

FIG. 11 is another perspective view thereof;

FIG. 12 is a front view thereof;

FIG. 13 is a left side view thereof;

FIG. 14 is a top plan view thereof;

FIG. 15 is a bottom plan view thereof;

FIG. 16 is a perspective view of the third part of the storage box;

FIG. 17 is another perspective view thereof;

FIG. 18 is a front view thereof;

FIG. 19 is a rear view thereof;

FIG. 20 is a left side view thereof;

FIG. 21 is an enlarged top plan view thereof; and,

FIG. 22 is an enlarged bottom plan view thereof.

The broken lines shown in the drawings illustrate portions of the storage box that form no part of the claimed design.

1 Claim, 22 Drawing Sheets
